CLAIM

The ornamental design for a housing for water filtration system, as shown and described.

DESCRIPTION

4. Housing for water filtration system

Figure 4.1 is a front view of the housing for water filtration system;

Figure 4.2 is a back view thereof;

Figure 4.3 is a left side view thereof;

Figure 4.4 is a right side view thereof;

Figure 4.5 is a top view thereof;

Figure 4.6 is a bottom view thereof; and

FIG. 4.7 is a view of the housing for water filtration system in an open state showing unclaimed interior environment thereof.

The broken lines depict portions of the housing for water filtration system that form no part of the claimed design.

1 Claim, 7 Drawing Sheets
